UNITED STATES PATENT OFFICE.

CHARLES D. WEEKS, OF AKRON, OHIO.

POTTERY-SPINNING WHEEL.

No. 895,060.

Specification of Letters Patent.

Patented Aug. 4, 1908.

Application filed June 30, 1906. Serial No. 324,267.

To all whom it may concern:

Be it known that I, CHARLES D. WEEKS, of Akron, in the county of Summit and in the State of Ohio, have invented a certain new 5 and useful Improvement in Pottery-Spinning Wheels, and do hereby declare that the following is a full, clear, and exact description thereof, reference being had to the accompanying drawings, in which—

10 Figure 1 is a side elevation of a spinning wheel embodying my invention; Fig. 2 a vertical section on the line 2—2 of Fig. 1; Fig. 3 a horizontal section on the line 3—3 of Fig. 2, and Fig. 4 is a detail view in side elevation of 15 the rib or former.

The object of my invention is to provide 20 a pottery spinning wheel whose operations shall be as automatic as possible, so as to reduce the manual labor required in the spinning operation to a minimum, and to this end, my invention consists in the spinning wheel constructed substantially as herein-after specified and claimed.

Referring to the drawings, which illustrate 25 one embodiment of my invention, 1 designates a suitable frame having bearings for a vertical shaft 2 that at its upper end carries a spinning wheel 3, the shaft being provided with a fast pulley 4 and a loose pulley 5 for alternate engagement by a belt 6 receiving motion from a suitable source. The shaft 2 is hollow or tubular, and vertically movable within it is a mold-lifting rod 7, which at its upper end has a head or cap 8 to 30 engage the bottom of a mold 9 in the spinning wheel. Also mounted in bearings in the frame 1 is a rotatable and vertically reciprocable rod or shaft 10 which, at its upper end, supports and carries a disk plate 11, 35 having in its edge a series—as shown four—of semi-circular notches 12, each adapted to receive and support a mold, for which purpose the mold is provided at its top with an annular flange formed by an annular groove 40 13 just below the top of the mold in a rim or flange on the mold that rests upon the upper edge of the spinning wheel, the mold being placed in and removed from engagement with the plate or disk-notch by a horizontal 45 movement of the mold. The rotation of the mold-supporting plate or disk is for the purpose of bringing the molds carried thereby successively into position in and out of alignment with the spinning wheel, and its vertical 50 movement is for the purpose of lowering a

mold into the spinning wheel, and then lifting it therefrom, these movements taking place in succession for the placing of a vessel to be operated upon in the spinning wheel and removing it therefrom, and all these 60 movements are produced automatically, as will be hereinafter more fully described.

The rib or former 14 which has an edge corresponding to the interior surface to be formed on the vessel is carried by an arm 15, 65 to which it is removably attached, so that ribs of different configuration may be employed, said arm being pivoted to a vertically reciprocable rod 16, so that the rib has a compound movement consisting of a vertical movement to project it into the vessel within the mold, and cause it to engage and operate on the interior surface thereof, and to lift the rib out of the mold, and of a swinging movement to carry it to one side of the 70 vessel in the mold when it has been removed therefrom, so that it will not hinder the lifting of the mold with the vessel therein from the spinning wheel, and to bring it again into position for action upon the vessel in the 75 mold. To impart this compound motion to the rib, its carrying arm at its pivoted end has attached to it a pinion 17, which on one side meshes with a stationary rack 18 fastened to the frame 1, and on its opposite side meshes 80 with a similar rack carried by a pitman 19, whose lower end is pivoted to a crank pin on a worm wheel 20, so that by the revolution of the latter the pitman is reciprocated and its rack, meshing with the pinion, revolves the latter, 85 thus imparting the swinging motion to the rib, and the vertical motion being produced by the action of the pinion upon the stationary rack 18. Contiguous to the path of the rib or former, just before it completes its 90 movement away from the vessel in the mold, is a plate or blade 21 conveniently made of sheet-metal supported by an arm 22 from the frame 1, and having an edge which will engage and clear or scrape from the rib or 95 former any clay which may adhere thereto.

To automatically shift the belt 6 from one pulley to the other, I attach to the vertically reciprocating rod 16 a belt shipper 23, which when the rib or former descends into the 100 vessel in the mold, shifts the belt into engagement with the fast pulley to cause the revolution of the spinning wheel, and which when the rib or former is lifted from the vessel in the mold, shifts the belt to the loose 110

pulley to stop the revolution of the spinning wheel, so that the rotation of the spinning wheel is automatically controlled.

The lifting of the mold-carrying plate or disk 11 is automatically accomplished by means of an arm 24 attached to and projecting at right-angles from the pitman 19 and a disk or wheel 25 on the rod or shaft 10 which supports said plate or disk, said arm being carried by the pitman into engagement with the underside of said wheel, and the disk or plate being thereby lifted, and to impart a partial revolution to said plate or disk to remove one mold from alinement with the spinning wheel and another mold into alinement therewith, ratchet teeth are provided on said wheel 25, there being a tooth for each mold-receiving notch in the disk or plate, and a stud or projection 26 carried by the arm 24 on the completion of the lifting of the mold-carrying disk or plate, moves horizontally into engagement with a ratchet tooth and thereby rotates the wheel and its shaft. On the descent of the arm 24, the mold-carrying disk or plate descends automatically by the action of gravity and places a mold with a new vessel to be operated on in the spinning wheel. Simultaneously with the rising and falling of the mold-carrying plate or disk, the mold-lifter is raised to lift the mold containing the finished vessel from the spinning wheel and descends back into the spinning wheel, the raising of the lifter being accomplished by means of an arm 27 attached to the vertically reciprocating rod 16 in such a position as to engage the lower end of the lifter-rod 7 when the vertically reciprocating rod 16 is raised, and the lifter descending by gravity as the arm 27 descends when its carrying-rod 16 moves downward. I also mount upon the vertically movable rod 16 a horizontal arm 28, which extends in position to have contact with the bottom of the spinning wheel to act as a stop or brake to arrest the revolution thereof by the time the belt is shifted from the fast to the loose pulley, thus avoiding the inconvenience which would result from the continued revolution of the spinning wheel and mold, due to their momentum.

Water or other liquid, such as coal oil, should be supplied to the vessel being molded, and I provide means for automatically delivering water to the interior surface of the vessel being operated on. Such means may have various forms. Thus I may provide a tank or receptacle 29 located sufficiently above the spinning wheel so that the liquid will pass therefrom through a tube or pipe 30 whose discharge end is at the proper point for the delivery of the liquid to the vessel being molded, the water or other liquid being supplied to the vessel by a pump 31 that is automatically operated by its piston being connected to the belt-shifter 23. A pipe or

tube 32 runs from the pump to the tank or receptacle. I preferably mount the tank or receptacle on the rib-carrying arm 15, so that the discharge of water may be controlled by the movements of said arm. Thus, when the arm is lowered or moved into position for operating on the vessel in the mold, the pipe 30 will be placed in such position that water will constantly flow or drip from the tank 30 into said vessel, while when said arm is lifted to take the rib out of the vessel in the mold, the pipe 30 will be lifted to cause the stoppage of the flow of water. I also mount on the arm 15 a tool to scrape or clean the upper edge of the mold, which consists of a shank 33 adjustably attached to the arm 15, and carrying a knife or blade 34 at its end to engage any clay adhering to the mold and scrape it off, when the arm 15 is in position to place the rib in the mold for operation. I also may provide for delivering a jet of water to the rib or former after each operation of the blade 21 on it, to wash it.

The operation of my spinning wheel is as follows:—With the mold - carrying disk or plate in an elevated position, molds with the vessels to be formed therein are placed, one at a time, in the notches or recesses in the plate or disk, and the latter, with the mold, directly above the spinning wheel, descends, carrying such mold into the spinning wheel, the pitman 19 descending at the same time, and through the rack and pinion mechanism described bringing the rib or former downward into the vessel, and also moving downward the bar which carries the belt-shifter 23, so that by the time the rib or former has reached its operating position, the belt will be shifted from the loose to the fast pulley, and the revolution of the spinning wheel with the contained mold will take place at a rapid rate of speed. The rib or former having operated on the vessel being made for the desired length of time, which is determined by the rate of revolution of the worm wheel 20, the pitman will, by its upward movement through the rack and pinion mechanism, lift the rib or former out of the vessel and swing it to one side, and at the same time, the belt shifter will move the belt from the tight to the loose pulley, and the mold-carrying disk or plate will be lifted to lift the mold containing the newly - formed vessel out of the spinning wheel, being supplemented by the mold lifter 7, and the lifting of the mold from the spinning wheel being accomplished, the mold - carrying disk or plate will be revolved a quarter of a turn to remove the mold with the newly-formed vessel from over the spinning wheel, and to bring the next mold with a vessel to be operated on into position over the spinning wheel, ready to be lowered therein. It will be observed that all the operations are automatically performed, excepting the mount-

ing of the mold with a vessel to be operated upon, on the mold-carrying plate or disk, and the removal of the mold with the completed vessel from the said disk or plate.

5 It is to be understood that it is not essential to the carrying of my invention into practice to employ the details of construction I have shown and described, and I, therefore, do not restrict myself in the practice of 10 my invention to the employment of the precise construction and arrangement of parts shown.

Having thus described my invention, what I claim is:—

15 1. In a pottery machine, the combination of a vessel-rotating means, a rib or former, automatic means acting at predetermined times to move the rib or former into and out of operating relation to the vessel, and means 20 imparting a compound movement to the rib or former composed of motions in swinging and rectilinear paths.

25 2. In a pottery machine, the combination of a vessel-rotating means, a rib or former, a pivoted support for the rib or former, and means for imparting movement to said support in circular and rectilinear paths, whereby a compound movement is imparted to the rib or former.

30 3. In a pottery machine, the combination of a vessel-rotating means, a rib or former, a pivoted arm carrying said rib or former, a movable support for said arm, and means for swinging the arm and moving said support in a straight line and in a direction to move the rib or former into or out of the vessel.

35 4. In a pottery machine, the combination of a vessel-rotating means, a rib or former, a pivoted arm carrying said rib or former, a movable support for said arm, and rack and pinion mechanism for swinging said arm and moving said support.

40 5. In a pottery machine, the combination of a spinning wheel, a mold support movable parallel with the axis of the spinning wheel, automatic means to impart its movements to said mold support, a rib or former, and automatic means acting at predetermined times to move the rib or former into and out of the 45 mold.

50 6. The combination of a spinning wheel, a mold support for a plurality of molds, a rib or former movable into and out of operating relation to the vessel, and automatic means to move the mold support to bring different molds in succession in operating relation to the spinning wheel, said automatic means being timed to operate the support with reference to the movements of the rib or former 55 into and out of the vessel.

60 7. In a pottery machine, the combination of a spinning wheel, and a mold support mounted for movement parallel with the axis of the spinning wheel and crosswise of such axis, whereby the mold may be moved 65

into and out of the wheel and towards and from the wheel.

8. In a pottery machine, the combination of a spinning wheel, a mold support for a plurality of molds mounted for movement 70 parallel with and crosswise of the axis of the spinning wheel, a rib or former mounted for movement into and out of a vessel in a mold, automatic means for imparting the described movements to the mold support, and automatic means for imparting the described movements to the rib or former. 75

9. In a pottery machine, the combination of a spinning wheel, a mold support for a plurality of rolls mounted for movement parallel with and crosswise of the axis of the spinning wheel, and automatic means for imparting said movements to the support in succession. 80

10. In a pottery machine, the combination of a spinning wheel, a mold-support adapted to support a plurality of molds, means for moving said support to place a mold into, and remove it from, engagement with the spinning wheel, and means to move said support to bring the molds in succession into position for engagement with the spinning wheel. 85

11. In a pottery machine, the combination of a spinning wheel, a mold support adapted to support a plurality of molds, means for moving said mold support to place a mold into engagement with the spinning wheel, and to remove it from such engagement, means to rotate said support step-by-step, means to start and stop the revolution of the spinning 100 wheel, a rib or former, and means to simultaneously actuate the rib or former, and the means for starting and stopping the revolution of the spinning wheel. 105

12. In a pottery machine, the combination of a rib or former, automatic means to move the rib or former into and out of operating relation to the vessel being formed, means for supplying a fluid to the vessel being formed, and a connection between said means and the 110 rib or former arranged to control the supply of fluid according to the position of the rib or former with reference to the vessel being formed.

13. In a pottery machine, the combination of a spinning wheel, a rib or former, movable into and out of position for operation, and a cleaner for the rib or former. 115

14. In a pottery machine, the combination of a spinning wheel, a rib or former, movable 120 into and out of position for operation, and a cleaner for the rib or former, consisting of a blade in position to engage the rib or former when it is moved to a position out of use.

In testimony that I claim the foregoing I 123 have hereunto set my hand.

CHARLES D. WEEKS.
